ATTORNEY

UNITED STATES PATENT OFFICE.

JOHN F. KELLY, OF TRENTON, NEW JERSEY, ASSIGNOR TO THOMAS MADDOCK'S SONS CO., OF TRENTON, NEW JERSEY, A CORPORATION OF NEW JERSEY.

LAVATORY.

1,424,250.

Specification of Letters Patent. Patented Aug. 1, 1922.

Application filed March 29, 1922. Serial No. 547,705.

To all whom it may concern:

Be it known that I, JOHN F. KELLY, a citizen of the United States, residing at the city of Trenton, county of Mercer, State of New Jersey, have invented certain new and useful Improvements in Lavatories; and I do hereby declare the following to be a full, clear, and exact description of the invention, such as will enable others skilled in the art

10 to which it appertains to make and use the same.

The invention relates to certain new and useful improvements in lavatories of the same general type as covered by Patent No. 15 1,406,030, dated February 7th, 1922, and has for its object to provide a self-contained faucet, especially applicable for drinking water, as a component part or element of a lavatory made of earthenware, vitreous 20 china, or the like, the invention comprising a chamber formed within the slab of the lavatory including a spout-like extension having an outlet opening overhanging the bowl, a valve of suitable type mounted within 25 the chamber and secured to the slab of the bowl and a discharge pipe connected to the valve casing at one end, extending through the chamber and the extension and attached, preferably by a perforated 30 threaded nipple at its outer end, within the outlet opening of said extension.

The invention is illustrated in the accompanying drawing, in which the figure is a fragmentary sectional elevation of an earthenware lavatory having the invention applied thereto.

Referring to the drawing, 1 indicates the slab of a typical lavatory of this type provided with a pendant apron or skirting 2 and 40 an integral bowl 3, which is preferably formed of china, clay or other vitreous material usually employed in manufacturing devices of this general character.

Formed in the body of the slab 1, and 45 preferably at one corner or at one end of the bowl, is a chamber 8, the top wall of which is an integral boss or projection 7, projecting above the normal surface of the slab. One end of the chamber forms a cylindrical 50 bore 11 extending from top to bottom through the slab and is adapted to receive the valve and its connections. The other end of the chamber 8 is constituted by an arcuate extension 9 having a discharge opening 55 overhanging the bowl, the rim of said open-

ing preferably being inclined at an acute angle to the plane of the slab to admit of a glass or drinking vessel being held under the discharge opening. The chamber 8 is open at its bottom to permit ready access to 60 the interior thereof for the purpose of applying and adjusting the valve and its accessories, and also to admit of the parts being readily cleansed.

Mounted in the chamber 8 is a valve of 65 any suitable type adapted to be connected with a supply pipe leading to a source of drinking water, which valve in turn is connected by an outlet pipe or nozzle which extends through the chamber and terminates 70 in a suitable nipple which secures the outer end of the discharge pipe to and within the discharge outlet of the extension 9. A convenient form of valve is illustrated in the drawing, and comprises tubular shell 12, 75 having its opposite ends provided with external screw-threads 15 and 16 to receive the lock nuts and packing washers 14 and 15 on the lower end, and 17 and 18 on the upper end, whereby the valve casing is securely 80 clamped in position within the cylindrical section 11 of the chamber 8 formed within the slab. The lower end of the valve casing 12 is internally screw-threaded to receive the end of a suitable supply pipe. The casing is provided with a valve seat 19 and a perforated partition 21, which guide the valve stem 26 having a valve disc or button 25 on the lower end thereof co-operating with the valve seat 19. The valve casing 12 90 is also provided with an outlet 20 formed in an externally threaded nipple 32. The upper end of the casing is fitted with packing washers 22 and 23, upon which is supported a helical spring 24, the tension of 95 which is adjusted by means of a set nut 27 working on the threaded upper end of the valve stem 26, which spring normally seats the valve. The upper end of the valve stem is provided with a knob 29 of any suitable 100 character, which is screw-threaded to the valve stem for ready removal and adjustment. The upper end of the valve casing is enclosed within a housing or cap 28, which, like the body of the knob, is preferably 105 made of the same material as the lavatory so as to produce a uniform finish in appearance with respect to the visible elements of the valve and the lavatory structure. The housing 28 is secured to the lock-nut 22 by 110

means of a screw-threaded ring 28' attached to the inner peripheral face of the housing so that the latter may be drawn down to tight engagement with the top surface of 5 the slab or the projection 7 thereof to prevent access and accumulation of dirt between the housing and the slab.

Having its inner end secured by a union coupling 31 to the boss 32 of the valve body, 10 is an outlet pipe 30, which, in the type of device illustrated, takes the form of a goose-neck having its outer end curved to generally conform to the curvature of the extension 9 of the chamber 8, the outer end of 15 the pipe being externally screw-threaded to engage a perforated nipple 34, which, if desired, may be made of vitreous ware, and is adapted to seat snugly within the rim of the discharge outlet of the extension 9, the 20 opening of the nipple registering with the bore of the pipe 30 and constituting the outlet for the water supply through the valve and the pipe 30.

The particular advantages of this specific 25 form of the invention are that it admits of the several parts being readily assembled and applied to proper position, provides an all-metal conduit for the water, and avoids the various pockets and recesses which would 30 tend to collect sediment and dirt, and, when properly assembled and applied to a lavatory, constitutes a strictly sanitary attachment to supply drinking water to the lavatory, without danger of the drinking 35 water or the faucet supplying the same becoming contaminated from the contents of the lavatory bowl.

What I claim is:

1. A drinking water supply for lavatories 40 comprising a chamber within the slab in-

cluding a spout-like extension having an outlet opening overhanging the bowl, a valve mounted in the chamber, and a discharge pipe connected to the valve casing extending through the chamber and extension and attached at its outer end within said outlet opening. 45

2. A drinking water supply for lavatories comprising a chamber within the slab including a curved spout-like extension having an outlet opening overhanging the bowl, 50 a valve mounted in the chamber, and a goose-neck discharge pipe connected to the valve casing extending through the chamber and extension and attached at its outer end within 55 said outlet opening.

3. A drinking water supply for lavatories comprising a chamber within the slab including a spout-like extension having an outlet opening overhanging the bowl, 60 a valve mounted in the chamber, a discharge pipe connected to the valve casing and extending through the chamber and extension, and a perforated nipple connected to the end of 65 said discharge pipe and seated in the outlet opening.

4. A drinking water supply for lavatories comprising a chamber within the slab including a curved spout-like extension having an outlet opening overhanging the bowl, 70 a valve mounted in the chamber extending through and secured to the slab, and a goose-neck discharge pipe connected to the valve casing extending through the chamber and extension, and a perforated nipple connected to the end of 75 said discharge pipe and seated in the outlet opening.

In testimony whereof I affix my signature.

JOHN F. KELLY.
